UNITED STATES PATENT OFFICE.

MALCOLM L. COSSITT, OF ALAMEDA, CALIFORNIA, ASSIGNOR TO MANIFOLD IMPRESSIONS CORPORATION, OF CARSON CITY, NEVADA, A CORPORATION OF NEVADA.

MANIFOLDING ATTACHMENT FOR TYPEWRITERS.

Application filed July 20, 1922. Serial No. 576,276.

To all whom it may concern:

Be it known that I, MALCOLM L. COSSITT, a citizen of the United States, residing at Alameda, in the county of Alameda and 5 State of California, have invented certain new and useful Improvements in Manifolding Attachments for Typewriters, of which the following is a specification.

My invention relates generally to that 10 class of manifolding attachments for typewriters in which a plurality of manifolding members are carried by movable arms mounted on the machine, and are adapted to be placed in and removed from functional 15 position in the line of type impact, and it concerns particularly means for selectively operating the carrying arms whereby one or more of the manifolding members may be used as required.

20 The object of my invention is to provide simple and effective selective means for this purpose, and to this end my invention consists in the novel manifolding attachment for typewriters which I shall hereinafter 25 fully describe by reference to the accompanying drawings, in which—

Fig. 1 is a front elevation, partly in section, of my manifolding attachment, showing the manifolding members and carrying 30 arms elevated.

Fig. 2 is an end elevation of the same from the left, showing by dotted lines its relation to the platen of a machine.

Fig. 3 is a sectional view enlarged, of 35 one set of carrying arms for the manifolding members, taken on the line III—III of Fig. 1, and showing the locking of the arms.

Fig. 4 is a side elevation, enlarged, of the 40 automatic arm-operating member.

Fig. 4^a is a side elevation of said arm-operating member at right angles to the elevation of Fig. 4.

Fig. 5 is a face or end view of said arm-operating member.

Fig. 6 is a perspective view of the first or innermost arm of one set or assembly of carrying arms.

Fig. 7 is a perspective view of the second or middle arm of said set of arms.

Fig. 8 is a perspective view of the third or outermost arm of said set.

Fig. 9 is an end view of one set of said arms, showing a modified position of the locking members.

Fig. 10 is a front elevation of the same. 55

Fig. 11 is a perspective view of one of the arms of the modified form of Figs. 9 and 10.

Fig. 12 is a section, enlarged, on the line XII—XII of Fig. 1. 60

Fig. 13 is a detail view showing the relative lengths of the arm lugs, and the operating member about to engage the longest lug.

1 indicates a pair of spaced brackets which are adapted for connection with the typewriter in any suitable manner conformably to the particular machine to which the manifolding attachment is applied. As such connection or mounting forms no part 65 of my present invention, and is not essential in the present condition and knowledge of the art, to a full understanding of the device for which I seek a patent, I have not deemed it necessary to illustrate it, since it would assume various forms according to 70 the particular machine with which the device is used. But in Fig. 2 I have illustrated by the dotted lines, the platen 2 of a typewriter, in order to show the positional relation of the device, adapting its manifolding members to be moved into and out 75 of their functional position in the line of type impact, which line, for the sake of simple illustration is here shown, in said Fig. 2, as on the top of the platen, though 80 it is to be understood that the position of this line and the relation of the device thereto will vary in different machines.

In and between the spaced brackets 1 is carried a shaft 3, adapted for rotation, a 85 knob 4 being provided for turning it, as seen in Fig. 1, the body of said shaft, between the brackets being preferably covered by a sleeve 5 which forms at its ends a guide and stop for the arm operating member 90 presently to be described.

Upon each end of the rotatable shaft 3 is pivoted an assemblage or set of carrying arms for the manifolding members. In each set I have here shown, for illustration three 100 arms 6, 7 and 8, lying one upon the other in nested relation, each arm being independently pivoted on the shaft and each adapted to be independently moved from the elevated position shown by the full lines in Fig. 105 2, to a depressed position shown by the dotted lines in said Fig. 2. Between the respective arms of each pair is stretched a

manifolding member, in the shape of a ribbon 9, which member is indicated in Fig. 1 by the dotted lines.

The arm 6 is the first or innermost arm, and as shown in Fig. 6, the base of this arm is provided with a laterally projecting lug 6'. The arm 7 is the second or middle arm, and as shown in Fig. 7, it is provided with a laterally projecting lug 7'. The arm 8 is the third or outermost arm, and as seen in Fig. 8, it is provided with a laterally projecting lug 8'. The lugs 6', 7' and 8', as seen in these figures, and especially in Fig. 13 have successively decreasing lengths, and are so positioned with relation to each other, that when the arms are assembled, the lugs lie one behind the other, the longest being in front, and they project in a line parallel with the rod, to successively decreasing distances, as seen in Fig. 13.

Upon the shaft 3, near each end is fitted the arm operating member 10, adapted to both turn with and to slide upon the shaft. This member, as shown in Figs. 1, 4, 5 and 12, is slotted over a cross pin 11 of the shaft, whereby it rotates with said shaft and can slide linearly therein, for which latter movement it is formed with a tubular shank 10' slidable on the shaft and within the sleeve 5 of said shaft, as seen in the sectional part of Fig. 1. A spring 12, Fig. 1, normally presses and yieldingly holds the operative member 10 out to its work.

The face of the operating member 10 is formed on one side with a double cam surface 13, Figs. 4a and 5, in the apex of which is a pick-up shoulder 14; and said face, opposite same cam surface has also an arm-returning lug 15, as shown in Fig. 4.

The operation of the device, as far as described, is as follows: In the normal, out of use position of the parts, as shown in Fig. 1, the arms are elevated, and the arm-returning lug 15 of the operating member 10 lies immediately in front of the longest lug 6', which is the lug of the innermost arm.

If, now, the shaft 3 be turned forwardly, as viewed in Fig. 1, that is counter clockwise, by its knob 4, it will rotate the operating member 10 forwardly until the first incline of the face cam 13 of said member, reaching and sliding upon the ends of the length-graduated lugs 6', 7' and 8' of the arms 6, 7 and 8, will cause said member to be forced linearly along the shaft, against the controlling spring 12. This linear movement of the member 10 will enable the pick-up shoulder 14 of said member to move freely past the shorter lugs 8' and 7' of the arms 8 and 7 without affecting said arms, but as the extremity of the first section of the cam is reached and it ceases to function, the operating member will spring forward and said shoulder 14 will engage be-

hind the long lug 6' of the arm 6, as seen in Fig. 13, and thereupon, continued rotation of the operating member 10 will pick-up said long lug 6' and will thus depress the arm 6 to the position shown by the dotted lines in Fig. 2 and carry the first manifolding ribbon down to the line of type impact, the other arms 7 and 8 remaining elevated.

If a second manifolding ribbon is required, the shaft 3 is turned in a reverse direction, and the shoulder 14 moves away from the depressed long lug 6'. The now retreating first section of the cam 13 riding on said lug allows the operating member to slide forward along the shaft, and this movement carries the opposite, advancing side or section of the cam into contact with the elevated lugs 7' and 8'. Riding on these lugs the operating member is then again slid back along the shaft, until the pick-up shoulder 14 drops in behind the second-length lug 7'. Then a forward rotation of the shaft causes the second arm 7 to be depressed. Finally another reversal of the shaft will cause the operating member 10 to return and pick up the short lug 8' of the third arm, and a forward movement of the shaft will then depress said arm. To return the arms, the shaft 3 is reversed far enough to cause its lug 15 to rise up under the depressed longest lug 6', and continued reverse movement will return all the lugs, arms and ribbons to their initial elevated position.

In order to yieldingly or releasably lock the arms, so that they may be neither inadvertently moved nor have any tendency, due to frictional juxtaposition to so move when any one is intentionally operated, the arms, as shown in Figs. 6, 7 and 8, are provided at their bases with the springy tongues 16 relatively so positioned in the several bases, as to not interfere with the nesting of the arms. These tongues yieldingly engage a notch 17—Fig. 3, in the bracket bearing 18 of the shaft 3.

The relative positions of these locking parts may be reversed, as shown in Figs. 9, 10 and 11, wherein the spring tongues 16' are carried by the brackets 1, and the notches 17' are in the base of the arms.

I claim:—

1. A manifolding attachment for typewriters comprising a rotatable shaft mounted on the machine; a plurality of independently operatable pairs of pivotally mounted spaced arms; a manifolding member carried by each pair of arms and adapted by the movement of said arms to be placed in and removed from functional position in the line of type impact; an arm-operating member fitted upon said shaft for rotation therewith and for linear movement thereon; means for controlling the linear movement of said member; and coacting devices on said mem- 120
125
130

ber and said arms for independently selectively moving each pair of arms about their pivotal centers, by the rotation of the shaft.

2. A manifolding attachment for typewriters comprising a rotatable shaft mounted on the machine; a plurality of independently operatable pairs of pivotally mounted spaced arms; a manifolding member carried by each pair of arms and adapted by the movement of said arms to be placed in and removed from functional position in the line of type impact; an arm-operating member fitted upon said shaft for rotation therewith and for linear movement thereon; means for controlling the linear movement of said member; and coacting devices on said member and said arms for independently selectively moving each pair of arms about their pivotal centers, by the rotation of the shaft; and means on said arms adapting them to be releasably locked at their limits of movement.

3. A manifolding attachment for typewriters comprising a rotatable shaft mounted on the machine; a plurality of independently operatable pairs of pivotally mounted spaced arms; a manifolding member carried by each pair of arms and adapted by the movement of said arms to be placed in and removed from functional position in the line of type impact; an arm-operating member fitted upon said shaft for rotation therewith and for linear movement thereon; means for controlling the linear movement of said member; and coacting devices on said member and said arms for independently selectively moving each pair of arms about their pivotal centers, by the rotation of the shaft, consisting of lugs of graduated length on the arms, a pick-up shoulder on said member and a cam on said member to selectively determine the contact of said shoulder with said length-graduated lugs.

4. A manifolding attachment for typewriters comprising a rotatable shaft mounted on the machine; a plurality of independently operatable pairs of pivotally mounted spaced arms; a manifolding member carried by each pair of arms and adapted by the movement of said arms to be placed in and removed from functional position in the line of type impact; an arm-operating member fitted upon said shaft for rotation therewith and for linear movement thereon; means for controlling the linear movement of said member; coacting devices on said member and said arms for independently selectively moving each pair of arms about their pivotal centers, by the rotation of the shaft; and means on said arms adapting them to be releasably locked at their limits of movement.

5. A manifolding attachment for typewriters comprising a rotatable shaft mounted on the machine; a plurality of independently operatable pairs of pivotally mounted spaced arms; a manifolding member carried by each pair of arms and adapted by the movement of said arms to be placed in and removed from functional position in the line of type impact; an arm-operating member fitted upon said shaft for rotation therewith and for linear movement thereon; means for controlling the linear movement of said member; coacting devices on said member and said arms for independently selectively moving each pair of arms about their pivotal centers, by the rotation of the shaft; and means for releasably locking said arms at their limits of movement, consisting of interengaging spring tongues and notches.

In testimony whereof I have signed my name to this specification.

MALCOLM L. COSSITT.
